[57] CLAIM

The ornamental design for a coffee server, substantially as shown and described.

DESCRIPTION

FIG. 1 is a perspective view of a coffee server embodying my new design;

FIG. 2 is a top plan view thereof;

FIG. 3 is a side elevational view thereof;

FIG. 4 is a bottom plan view thereof;

FIG. 5 is a side elevational view thereof taken of the side opposite to that shown in FIG. 3;

FIG. 6 is a rear elevational view thereof;

FIG. 7 is a front elevational view thereof.

Fig. 1.

*Fig. 2.**Fig. 3.**Fig. 4.**Fig. 5.**Fig. 6.**Fig. 7.*
